UNITED STATES PATENT OFFICE.

FRANCIS SKINNER ANDERTON, OF BLACKBURN, ENGLAND.

STEAM SUPERHEATER.

Application filed June 1, 1926, Serial No. 112,942, and in Great Britain September 9, 1925.

This invention relates to superheaters for steam generators wherein U shaped or other tubes are secured at their ends to headers. In this type of superheater it is customary to bend the ends of the tubes outwardly in the form of crooks and to expand the ends of the tubes in groups of two or more into plates which are secured to the tops of the headers by studs and nuts. With this construction a tube cannot be expanded when in position owing to its ends being crooked or bent and in the event of any one tube in a group becoming damaged it is necessary to remove all the tubes in that group from the header in order to repair or replace the damaged tube.

According to this invention single U shaped or other tubes are attached to headers in such manner that their ends can be expanded whilst in position and any individual tube can be removed and replaced without disturbing any of the others and without displacing the brickwork, or setting. Any tube which is not required can be withdrawn and replaced by a stopper.

For this purpose the end of each tube is expanded into a tubular casting formed with a closable aperture opposite to the tube and with a spigot adapted to enter an aperture in the header and make a tight joint therewith.

In the accompanying drawings:—

Fig. 1 is a plan of part of a steam superheater constructed according to this invention.

Fig. 2 is a section taken on line 2—2 of Fig. 1.

Fig. 3 is a section of one of the tubular castings drawn to a larger scale, and

Fig. 4 is a plan of the casting shown in Fig. 3.

A indicates the U shaped tubes, B the headers, and C the tubular castings.

In carrying out the invention each of the tubular castings C may be constructed from steel and may terminate at one end in a T piece c and at the other end in an elbow c⁵. The end of the tube A is expanded into one branch of the T piece by an expanding tool which is inserted through the other branch. This branch is normally closed by a flanged plug c² which is tapered to fit into a tapered hole in the branch and is secured therein by bolts and nuts c³, the bolts passing through lugs c⁴ on the branch and flanged plug. If desired a jointing ring may be interposed between the flange on the plug and the mouth

of the branch. The branch pipe of the elbow is tapered at c⁵ to enter a tapered hole in the header B. It may also be formed with a flange such as c⁶ and a jointing ring may be 60 inserted between such flange and the header. The holes in the header which receive the aforesaid tapered portions are staggered as shown in Fig. 1 so that when the tubes A are placed in position they occupy a staggered 65 relationship to one another between the two headers. The castings C may be secured to the headers by plates D which may be held in position by collared studs d screwed at intervals into the headers. These plates occupy a position above the tops of the castings C and each plate is formed with a number of tapped holes d¹ which occupy a position centrally above the branch pipes of the elbows. Screwed into each of these holes is a set 75

screw d² for exerting pressure upon a thickened portion c⁷ of the casting C and causing the tapered end of the branch pipe to be forced tightly into the tapered aperture in the header. With this construction the end 80 of any tube can be expanded as and when required whilst it is in position by removing the flanged plug c² and inserting and actuating an expanding tool. Any tube that is not required can be taken out, a tapered 85 flanged stopper or plug is then inserted into the tapered aperture in the header and secured by its respective set screw in the plate. The plates D are advantageously made in short lengths which contact with one another and one or more removable cover plates E span the distance between the plates D. Round or other suitably shaped headers may be substituted for the ones shown.

What I claim as my invention and desire 95 to secure by Letters Patent in the United States is:—

1. In a steam superheater, a header having a plurality of apertures, a plurality of tubular castings each having a spigot fitted 100 in one of said apertures, a plurality of tubes having ends secured in said castings, the castings having apertures opposite to the ends of the tubes, removable closures for the last named apertures, a plate connected with the header and extending across said castings opposite to the header, and set screws extending through said plate and engaging said castings to force the spigots into the first named apertures.

2. In a steam superheater, spaced headers each having a plurality of apertures, a plu-

rality of tubes intermediate said headers, a separate tubular casting for each end of each tube, the ends of the tubes being secured in said castings and the castings having apertures opposite to the ends of the tubes, removable closures for the last named apertures, each casting having a spigot fitted in one aperture of one header, plates connected to the headers and extending across

said castings opposite to the headers, set 10 screws extending through said plates and engaging said castings to force said spigots into the first named apertures, and a cover extending across the space between said plates.

15

In witness whereof I have signed this specification.

FRANCIS SKINNER ANDERTON.
